Primary Examiner — Cynthia Ramirez*Assistant Examiner* — Michael Maharajh(74) *Attorney, Agent, or Firm* — Eversheds Sutherland (US) LLP(57) **CLAIM**

We claim the ornamental design for a waste receptacle, as shown and described.

DESCRIPTION

FIG. 1 is an upper perspective view of a waste receptacle, showing our new design;

FIG. 2 is a lower perspective view showing the design of FIG. 1;

FIG. 3 is a front view showing the design of FIG. 1;

FIG. 4 is a back view showing the design of FIG. 1;

FIG. 5 is a left side view showing the design of FIG. 1;

FIG. 6 is a right side view showing the design of FIG. 1;

FIG. 7 is a top view showing the design of FIGS. 1; and,

FIG. 8 is a bottom view showing the design of FIG. 1.

The evenly spaced broken lines shown in the figures are for the purpose of illustrating portions of the waste receptacle and form no part of the claimed design. The dash-dot lines represent claim boundaries and form no part of the claimed design.

1 Claim, 8 Drawing Sheets(56)
